UNITED STATES PATENT OFFICE.

LINCOLN M. STEARNS, OF YOUNGSTOWN, OHIO.

FILE.

1,322,642.

Specification of Letters Patent. Patented Nov. 25, 1919.

Application filed February 29, 1916. Serial No. 81,090.

To all whom it may concern:

Be it known that I, LINCOLN M. STEARNS, a citizen of the United States, residing at Youngstown, county of Mahoning, State of 5 Ohio, have invented a new and useful File, of which the following is a specification.

My present invention consists of a novel file which is especially adapted to receive and retain in a flat and unwrinkled condition tracings, drawings and other papers in 10 such a manner that they may be readily removed when desired.

It further consists of a novel file having upright or vertical partitions of skeleton 15 formation suspended within the cabinet or case and wherein the walls of the partitions form the means to grip the articles inserted between them.

It further consists of a novel file having 20 an upright pocket suspended from its top and open at its upper end and having its bottom consisting of a flexible loop, with the sides of the pocket above the loop stiff and constituting guides for the folders which 25 are to be inserted.

Other novel features of construction and advantage will hereinafter more clearly appear in the detailed description of my invention.

For the purpose of illustrating my invention, I have shown in the accompanying drawings certain embodiments thereof which are at present preferred by me, since the 30 same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view partly broken away of a filing cabinet and files, embodying my invention.

Fig. 2 represents a section on line $x-x$ of Fig. 3.

Fig. 3 represents a longitudinal section of Fig. 1.

Fig. 4 represents a sectional elevation of 50 another embodiment of my invention.

Fig. 5 represents a section on line $y-y$ of Fig. 4.

Fig. 6 represents a sectional elevation of another embodiment of my invention.

Similar numerals of reference indicate 55 corresponding parts in the figures.

Referring to the drawings.

Referring first to Figs. 1 to 3 inclusive, 1 designates the cabinet or case which may 60 have any desired or conventional contour. The cabinet may be supported in any desired manner and for convenience of illustration is shown as provided with antifriction devices 2 such as casters, which may be 65 omitted if desired. The cabinet is open at its upper end as at 3 and such opening is covered by a sectional curtain 4 the sections 70 of which are connected at their top to cross bars 5 the ends of which are guided in channel bars 6 mounted within the cabinet. The cross bars 5 are provided with handles 7. The curtain 4 when in open position is concealed between the plates 8 which are connected to or carried by the side walls of the 75 cabinet in any desired manner and at their upper ends they are curved laterally and terminate within the top of the cabinet, as will be understood by reference to Fig. 1. 9 designate angle bars which are connected 80 by means of angle brackets 10 with the cabinet. The angle bars 9 are cut as at 11 to form seats to receive supporting bars 12 to which latter compression strips 13 have their upper ends connected, as at 14, by 85 riveting, welding or any other desired manner. The bars 12 near their ends are cut out as at 15 to form tongues 16. The compression strips 13 near their bottoms are cut out as at 17 to form tongues 18 which are freely 90 movable in the transversely extending channel bars 19 carried by the bottom of the casing. The bars 19 may have any desired shape in cross sections and for purpose of illustration are shown as substantially U 95 shaped.

20 designate longitudinally extending spaced plates connected with the side walls of the cabinet by welding or in any other desired manner. These plates are preferably provided with offset flanges 21 secured to the cabinet by fastening devices 22. The compression strips 13 carried by a bar 12 have located between them springs 23 which I have preferred to illustrate as of helical 100 formation with their end portions secured to their respective compression strip. As shown, the ends of the springs pass through

extruded blisters 24. The compression strips 13 are formed from sheet metal preferably of about sixteen or eighteen gage which renders the partitions so stiff that the 5 springs will not bend them or exert a localized pressure on the papers between the partitions.

In the embodiment shown in Figs. 4 and 5 the partitioning members are formed, supported and guided in a different manner from that seen in Figs. 1 to 3 inclusive. The cabinet is constructed in a similar manner to that seen in Figs. 1 to 3 inclusive except that channel bars 25 located at opposite sides of 15 the cabinet have foot flanges 26 fixed with respect to the side walls of the cabinet in any desired manner. 27 designate supporting bars the ends of which are slidably mounted on the channel bars 25. 28 designate 20 compression strips secured to the bars 27 in any desired manner. The upper ends of a set of compression strips are refolded or deflected downwardly, as at 29, to engage the ends of a strip of fabric 30. Each strip 25 of a set has its lower end recessed at opposite sides as at 31 to form a T or tongue 32 and Z bars 33 are provided at the bottom of the cabinet to guide the lower ends of the compression strips. 34 designate bars carried 30 by the compression strips and forming therewith a skeleton partition. 35 designates reinforcing plates corresponding to the plates 20 in Fig. 1. 36 designates springs having their ends connected to the compression strips of a set in a similar manner to 35 that already described with respect to Figs. 1 to 3 inclusive.

In the form shown in Figs. 4 and 5 I preferably employ upper, lower and intermediate springs. The purpose of the connection 30 at the top is to prevent the accidental dropping of folders between the backs of the compression strips.

In the embodiments seen in Figs. 1 to 5 inclusive the partitioning members are not connected at their bottom to form pockets and are not flexible in the sense that the springs exert a localized pressure or bend them.

50 In Fig. 6, I show another embodiment of my invention in which juxtaposed compression strips have their lower ends connected by a flexible strip or loop to form a pocket, the walls of which are of skeleton formation and are provided with stiff upright side members which constitute guides and against which the compression springs bear to retain the folders in their respective pockets.

60 37 designate the compression strips, seen in Fig. 6, which are connected at their upper ends to supporting bars 38 the ends of which are seated in the slots 39 in the bar 40. 41 designate compression springs connected

with juxtaposed compression strips. The 65 lower ends of two adjacent compression strips are deflected upwardly to clamp the ends of a flexible unsupported loop 42 which forms a flexible bottom for the upright or vertical pocket or receptacle which is to receive the folder. The pocket formed by the compression strips and flexible loops is suspended wholly from its upper end and is of skeleton formation. The bottom of the pocket terminates preferably short of the 70 bottom of the case and is entirely free and unsupported in order that the bottom edge of the folder may be centered. The construction seen in Fig. 6 differs from that seen in Figs. 1 to 3 inclusive in that adjacent 75 compression strips, instead of being guided and freely movable at their bottom, are connected by a flexible loop forming therewith a pocket with a flexible bottom.

The metallic side members of the filing 80 spaces in Figs. 1 to 5 inclusive, and of the pockets in Fig. 6, are preferably smooth and relatively stiff and facilitate the insertion of the folders.

For the sake of clearness of illustration 90 and since their use is well understood by those skilled in this art, I have deemed it unnecessary to illustrate the folders which fit into the filing spaces or into the pockets.

The compression strips form stiff upright 95 side members against which the compression springs bear.

In all of the embodiments of my invention, I employ stiff upright members to form the skeleton wall of the filing space so that the gripping action due to the compression springs is not localized but is distributed throughout substantially the entire surface of the members which contact with the folders. In other words, the wall of the filing 100 space is not deflected out of its normal plane or distorted by the compression springs. It will be apparent that juxtaposed metal parts may be connected by welding, riveting or in any other desired manner.

110 It will now be apparent that I have devised a novel and useful file which embodies the features of advantage enumerated as desirable in the statement of the invention and the above description, and while I have, in the present instance, shown and described preferred embodiments thereof which will give in practice satisfactory and reliable results, it is to be understood that the same are susceptible of modification in various 115 particulars without departing from the spirit or scope of the invention or sacrificing any of its advantages.

Having thus described my invention, what I claim as new and desire to secure by Letters Patent is:

1. A file comprising a series of upright partitions suspended at their upper ends and

forming filing spaces, and means to guide the lower ends of said partitions.

2. A file comprising a series of upright compression strips suspended at their upper 5 ends and forming filing spaces with walls of skeleton formation, the filing spaces being open at their top and bottom, and guides for the lower ends of said strips.

3. A file comprising a series of upright 10 compression strips suspended at their top and forming filing spaces with walls of skeleton formation, compression springs bearing against said strips, and guiding means for the lower ends of said strips.

15 4. A file comprising a series of stiff upright compression strips suspended at their top and forming filing spaces with walls of skeleton formation, compression springs bearing against said strips, and guiding 20 means for the lower ends of said strips.

5. A file comprising a cabinet, cross bars carried thereby, compression strips secured at their upper ends to said cross bars and having their lower ends disconnected to 25 form upright filing spaces, and bars carried by said cabinet and serving as guides for the lower ends of the compression strips.

6. A file comprising a series of upright 30 partitions suspended at their upper ends and of skeleton formation, with juxtaposed partitions disconnected at both their tops and their bottoms.

7. A file comprising a cabinet having an open top, bars fixed within the upper 35 portion of the cabinet, cross bars mounted on said bars, compression strips having their

upper portions fixed to said cross bars and forming filing spaces with skeleton walls of stiff upright members, compression springs bearing against said members, and guiding 40 devices for the lower ends of said members.

8. A file comprising a cabinet having an open top, bars fixed within the upper portion of the cabinet, cross bars mounted on said bars, compression strips having their 45 upper portions fixed to said cross bars and forming filing spaces with walls of stiff upright members, compression springs bearing against said members, said strips having cut out portions at their lower ends, and bars 50 having means to extend into said cut out portions to guide the lower ends of said strips.

9. A file comprising a cabinet having an open top, a curtain covering said top, means 55 to guide said curtain, supporting bars within said cabinet, stiff upright members arranged in sets with their upper ends fixed at opposite sides of said bars and spaced apart to form skeleton walls of filing spaces 60 open at their top and bottom, and means to guide the lower ends of said members.

10. A file comprising a series of upright partitions suspended at their upper ends and forming filing spaces, means to guide 65 the lower ends of said partitions, a curtain covering the top of said file, and means to guide said curtain.

LINCOLN M. STEARNS.
